BODKIN FABRICATING MACHINE

Louis Halper, Brooklyn, N. Y.

Application December 24, 1940, Serial No. 371,539

2 Claims. (Cl. 153—1)

This invention relates to machines for capping wire ends and especially to machines for fabricating bodkins.

In various types of clothing, especially uniforms and the like, in which decorative buttons are used, it has been the practice not to sew the buttons directly upon the uniform, but rather to detachably engage the buttons to the garment. This has been done in various ways. One of the ways is that of slidably mounting the button eye upon a bodkin having an elongated eye.

One of the best methods of making such bodkins is the forming thereof from wire and then capping the two free wire ends. Since the point of the bodkin must be passed through all different kinds of fabric, it is desirable that the point be relatively smooth, that is to say, that the point have no undesirable roughness or protuberances which would interfere with the passing of the bodkin point through the fabric. Normally, in order to facilitate the passage of the bodkin point through the fabric and to properly position the buttons with relation to the garment, the garment is provided with a series of eyelets which are reinforced at the edges thereof by embroidery or other stitching.

The present invention is concerned principally with a machine for the quick and easy application of the bodkin cap to the free ends of the wires forming the bodkin, so that a smooth and otherwise desirable bodkin point is produced.

Among the objects of the invention lies the provision of bodkin capping structure which is relatively low in cost and highly efficient in use.

Another object herein lies in the provision of a machine of the class described which will accurately and uniformly cap bodkin ends.

Another object herein lies in the provision of a machine having the above described characteristics, yet which is simple and economical in operation, and which may be either driven by hand or foot operating mechanism.

These objects and other incidental ends and advantages will more fully appear in the progress of this disclosure and be pointed out in the appended claims.

In the drawings constituting a material part hereof, similar reference characters designate corresponding parts throughout the several views in which:

Figure 1 is an enlarged elevational view showing a completed bodkin assembly including the button, bodkin, and cap.

Figure 2 is a view taken similarly to Figure

1, showing the parts in position just prior to assembly.

Figure 3 is a view taken similarly to Figure 2 with the exception that the bodkin has been rotated through 90° about a vertical axis.

Figure 4 is an enlarged fragmentary view partly in section showing the manner in which the bodkin cap is maintained upon the wire ends of the bodkin.

Figure 5 is a view in perspective showing the die-pliers with a button and bodkin in place just prior to the capping operation.

Figure 6 is an enlarged fragmentary sectional view as seen from the plane 6—6 on Figure 5, most of the parts being shown in elevation.

Figure 7 is an enlarged side elevational view partly in section, showing the bodkin machine in position just prior to the capping operation.

Figure 8 is a horizontal sectional view as seen from the plane 8—8 on Figure 7.

Figure 9 is an enlarged vertical sectional view as might be seen from the plane 9—9 showing the parts in a position which they occupy at the beginning of the actual capping operation.

In accordance with the invention, the bodkin assembly 10 comprises generally a button 11, having a face 12, a back 13, and a button eye 14. For most purposes, more satisfactory operation is obtained when the eye 14 is adapted to swivel slightly with relation to the back 13. Also included in the bodkin assembly 10 is a bodkin 15 and the bodkin cap 16. The bodkin itself is preferably a U-shaped wire form and includes the arms 17 and 18 which have the straight ends 19 and 20, the button eye centering portions 21 and 22, the inwardly curved portions 23 and 24, and the outwardly curved portions 25 and 26, respectively. The portions 21 to 26, inclusive, form a slot or bodkin eye, generally indicated by numeral 27. The straight ends 19 and 20 on the outwardly disposed surfaces thereof are provided with notches 28 and 30.

The die-pliers are generally indicated by numeral 35 and the construction thereof is best seen in Figures 5 to 9, inclusive, of the accompanying drawings. The die-pliers 35 comprise generally a pair of pivotally interconnected levers 36 and 37. The levers 36 and 37 include jaw portions 38 and 39, pivotal portions 40 and 41, handle portions 42 and 43, and a rivet 44. The levers are pivotally interconnected at the pivotal portions 40 and 41 by means of the rivet 44. The jaw portions 38 and 39 have the outer vertical walls 46 and 47 thereof preferably planar and parallel, while the ends 48 and 49 of the jaws

are preferably in the same plane, flat, and disposed at right angles to the walls 46 and 47. The top walls 50 and 51 are preferably flat and parallel to the bottom walls 52 and 53. The inner opposed faces of the jaw portions 38 and 39 have working faces 54 and 55. The working faces 54 and 55 are provided with semi-cylindrical cap lower flange retaining portions 56 and 57, rim crimping portions 58 and 59, bodkin straight end engaging portions 60 and 61, bodkin button eye centering portion engaging recesses 62 and 63, respectively. As seen in Figure 9, the cap 16 includes a rounded head 64, and a cylindrical downwardly extending flange 65. The internal diameter of the flange 65 is preferably slightly greater than the greatest distance between the outer surfaces of the straight ends 19 and 20 when the inner opposed surfaces of said ends are in contact. The flange retaining portions 56 and 57 are each semi-cylindrical in shape so that when the jaw portions 38 and 39 are brought together, the outer surface of the flange 65 makes a sliding fit therebetween. The straight end engaging portions 60 and 61 are each provided with a U-shaped vertical groove adapted to engage the end portions 19 and 20. The depth of said U-shaped groove is such that when the working faces 54 and 55 are in their closed position, the straight ends 19 and 20 are tightly clamped therebetween. The rim crimping portions 58 and 59 are of curved configuration and converge from the flange retaining portions 56 and 57 to the straight end engaging portions 60 and 61. The recesses 62 and 63 are adapted to engage the outer surfaces of the button eye centering portions 21 and 22. The total vertical thickness of the jaw portions 38 and 39 is such that when the button eye centering portions 21 and 22 are fully upwardly seated within the recesses 62 and 63, the upper terminals of the straight ends 19 and 20 will be disposed slightly above the top walls 50 and 51, and the notches 29 and 30 will be positioned adjacent the lower edges of the rim crimping portions 58 and 59, as best seen in Figure 9 of the accompanying drawings. The convenient operation of the die-pliers 35 may be facilitated by the incorporation of a small expansive spring 66 shown in Figures 6 and 8, the ends of the spring 66 are suitably anchored within the handle portions 42 and 43.

The press generally indicated by numeral 70 includes an operating lever 71, a frame 72, a base 73, a ram 74, and a bolster 75. The ram 74 is provided at the lower end thereof with a bore within which is seated the punch 76. The punch 76 is maintained in place in any suitable manner, as for example, by means of the set screw 77. The upper end of the ram 74 has integrally extending therefrom a concentrically disposed drive rod 78. The upper end of the drive rod 78 acts as a follower for the cam 79 on the operating lever 71. The lower inner end of the operating lever 71 is pivotally connected to the frame 72 by the pin 80. The drive rod 78 and the ram 74 are maintained in the normal upper or retracted position thereof (see Figure 9) by the action of an expansive coil spring 81, which is seated in a suitable bore in the frame 72. The upper end of the spring 81 is articulately associated with the drive rod 78 by means of the washer and pin structure 82.

The operating lever 71 may be maintained in its upper position thereof (as shown in Figure 7) by means of a counter-weight disposed to the left of the pin 80, as seen in said Figure, said counter-

weight being well known in press construction, and therefore not shown in the drawings.

The frame 72 is provided with an outward extension 83 in the upper surface of which is mounted a bolt 84, having a lock-nut 85. Adjustment of the bolt 84 and lock-nut 85 serves to regulate the downward travel of the operating lever 71, which strikes thereagainst.

The punch 76 has the lower terminal thereof shaped to conform to the upper and outer surface of the rounded head 64, as seen in Figure 9. The bolster 75 is of irregular configuration, best seen in Figures 7, 8, and 9. The working surface 86 of the bolster is provided with an open ended slot 87, and with a U-shaped guide portion 88. The inner opposed surfaces of the arms of the U-shaped guide portion 88 are parallel and are spaced from each other a distance substantially equal to or only slightly greater than the distance between the outer vertical walls 46 and 47 of the die-pliers 35. The cross piece 89 of the guide portion 88 is provided with a screw 90 and a lock-nut 91. By adjusting the screw 90 and the lock-nut 91, the position of the die-pliers 35 with relation to the bolster and hence with relation to the punch 76 and the ram 74 is thereby regulated.

Operation

First a bodkin 15 is manually grasped, the same appearing as seen in Figure 2. A button 11 is grasped and the eye 14 slipped over the terminals of one of the straight ends 19 or 20, as for example, as shown by the dot-dash lines on Figure 2 on which the button eye has been slipped over the terminal of the end 19. The button is then pushed downwardly so that the same takes the position of the button 11 in Figure 1, where the eye 14 lies between the outwardly curved portions 25 and 26.

At this point, in one method, the straight ends 19 and 20 are placed between the working faces 54 and 55 of the die-pliers 35 with the button eye centering portions disposed within the recesses 62 and 63. The handle portions 42 and 43 are manually moved toward each other and the jaw portions 38 and 39 are inserted between the arms of the U-shaped guide portion 88. A cap 16 is placed upon the terminals of the straight ends 19 and 20 so that the lower rim of the flange 65 engages the rim crimping portions 58 and 59.

An alternate method is to squeeze the ends 19 and 20 toward each other, place a cap 16 thereon, and then grasp the assembly between the die-pliers.

The screw 90 and lock-nut 91 are adjusted until the center of the rounded head 64 lies directly below the center of the corresponding female depression in the punch 76. The bolt 84 and the lock-nut 85 are adjusted so that the ram when moved to its lowermost position will press the punch 76 against the head 64 and force the lower rim of the flange 65 against the crimping portions 58 and 59 an amount sufficient to crimp the said lower rim about the ends 19 and 20. The lower rim of the flange 65 will then enter the notches 29 and 30 where they exist, and where they do not exist, will be compressed and rounded toward the portions of the ends 19 and 20 immediately adjoining.

After the cap 16 has been properly seated, the die-pliers 35 are removed from the bolster 75, the working faces thereof are separated and the completed button and capped bodkin will drop therefrom.

In use, the button and bodkin are inserted through the garment opening in a position shown in Figure 1, and after the bodkin has completely passed through the garment, the bodkin is slid along the button eye 14, until the button takes a position shown by the dot-dash lines on Figure 2, the button being disposed on one face of the garment and the bodkin on the other.

It may thus be seen that there has been provided a novel bodkin capping machine which may be constructed at relatively low cost and is efficient in operation so that capped bodkins may be produced in large numbers at high speed and low cost. The machine is most efficiently operated when the die-pliers are manipulated with the left hand and the operating lever 11 as well as the insertion and the removal of the bodkins from the pliers is accomplished with the right hand. The operation would then face the machine as shown in Figure 7.

I wish it to be understood that I do not desire to be limited to the exact details of construction shown and described for obvious modifications will occur to a person skilled in the art.

I claim:

1. For use with a bodkin assembly including a bodkin and a cap, a bodkin capping machine comprising: die pliers including a pair of pivotally interconnected levers each having a jaw portion and a handle portion, each jaw portion having a working face provided with a cap lower flange retaining portion which is semi cylindrical in horizontal section, a rim crimping portion which is generally concave having the configuration of a portion of a sphere and the walls of which are downwardly converging, a bodkin straight end engaging portion disposed below and continuing downwardly from the narrowest part of said rim crimping portion, said bodkin straight end engag-

ing portion being U-shaped in horizontal section, and a bodkin button eye centering portion engaging recess which extends deeper into said jaw portion than said bodkin straight end engaging portion, said working faces being oppositely disposed and adapted to support the bodkin and cap during the capping operation; and means to support the die pliers; and means to force the bodkin cap longitudinally of the bodkin ends.

- 10 2. For use with a bodkin assembly including a bodkin and a cap, a bodkin capping machine comprising a press with a bolster and a ram reciprocable with relation to said bolster; said bolster having a guide portion; die pliers including a pair of pivotally interconnected levers each having a jaw portion and a handle portion, each jaw portion having a working face provided with a cap lower flange retaining portion which is semi cylindrical in horizontal section, a rim crimping portion which is generally concave having the configuration of a portion of a sphere and the walls of which are downwardly converging, a bodkin straight end engaging portion disposed below and continuing downwardly from the narrowest part of said rim crimping portion, said bodkin straight end engaging portion being U-shaped in horizontal section, and a bodkin button eye centering portion engaging recess which extends deeper into said jaw portion than said bodkin straight end engaging portion, said working faces being oppositely disposed and adapted to support the bodkin and cap during the capping operation; said die pliers having the jaw portions thereof insertable in the guide portion of the bolster; said 30 ram in a lowered position thereof being adapted to force the bodkin cap longitudinally of the bodkin straight ends.

LOUIS HALPER.
